[57] CLAIM

The ornamental design for a strip for water sealing steel bath tubs from studs and dry wall, as shown and described.

DESCRIPTION

FIG. 1 is a perspective view of a strip for water sealing steel bath tubs from studs and dry wall, showing my new design, the broken line showing is for illustrative purposes only and forms no part of the claimed design; FIG. 2 is an end view, the opposite side being a mirror image thereof;

FIG. 3 is a side elevational view thereof;

FIG. 4 is a top plan view thereof;

FIG. 5 is a side elevational view thereof; and,

FIG. 6 is a bottom view thereof.
